UNITED STATES PATENT OFFICE.

PETER ALBANO, OF CHICAGO, ILLINOIS, ASSIGNOR TO JOHN A. COLBY & SONS, OF CHICAGO, ILLINOIS, A CORPORATION OF ILLINOIS.

TABLE.

1,086,800.

Specification of Letters Patent.

Patented Feb. 10, 1914.

Application filed January 20, 1913. Serial No. 743,081.

To all whom it may concern:

Be it known that I, PETER ALBANO, a subject of the King of Italy, residing at Chicago, in the county of Cook and State 5 of Illinois, have invented new and useful Improvements in Tables, of which the following is a specification.

My invention relates to tables of the extension type, and my object, generally stated, 10 is to provide a novel and simple construction of extension table, the sections of the top of which, by preference, are self-contained in the table, thereby avoiding the objectionable use of top sections, or boards, 15 separate from the table, which require storing when not in use.

Referring to the accompanying drawings, Figure 1 is a top plan view of a table constructed in accordance with my invention, 20 the full line representation of the top sections thereof showing one of the top sections in the position it assumes when the table is contracted and the other section thereof in the position it assumes when extended to coöperate with other sections to 25 form the extended top. Fig. 2 is a section taken at the line 2 on Fig. 1 and viewed in the direction of the arrow. Fig. 3 is a section taken at the line 3 on Fig. 4 and 30 viewed in the direction of the arrow, this view showing a desirable form of lock for securing certain of the top sections of the table together when in extended condition. Fig. 4 is a top plan view showing the table 35 in extended condition, portions of the tabletop being broken away; and Fig. 5 a section taken at the line 5 on Fig. 4 and viewed in the direction of the arrow.

The base of the table, the dimensions of 40 which, in accordance with the preferred embodiment of my invention, remain unchanged in extending the table, is represented at 6. As shown, it is formed of four legs 7 located at its corners and which, in 45 practice, would be preferably braced together, and a frame-section at its upper end secured to the legs 7 and composed of the side and end-pieces 8 and 9 respectively, a bar section 10 extending longitudinally of 50 the base and connected at its ends with the end-pieces 9, and transversely extending sections 11 located intermediate the ends of the table and connected with the side-pieces 8 and bar 10, the inner surfaces of the side-

pieces 8 and the bar section 10 containing 55 longitudinally extending grooves 12 which extend approximately the full length thereof.

The top of the table is formed of four sections 13, 14, 15, and 16 of the same dimensions, mounted on the base 6, and extending longitudinally of the grooves 12. The said top sections are connected together in pairs, the sections 14 and 16 being superposed on the sections 13 and 15, respectively, 60 when the table is in contracted condition. The sections 13 and 15 carry, on their under sides, longitudinally extending bars 17 provided with tongues 18 guidedly confined in the grooves 12 in the side sections 8 and 70 bar 10, and are connected along their inner edges with the sections 14 and 16, respectively, by hinges 19, whereby when the pairs of top sections, connected together as described, are slid in opposite directions on 75 the base 6 to extend the table, as hereinafter described, the sections 14 and 15 may be swung on the respective sections 13 and 16 to occupy the spaces thus produced at the diagonally disposed corners of the table top. 80

The tongue-equipped bars 17 are preferably of such length and so positioned that when the sections 13 and 14 and 15 and 16 occupy positions wherein they extend side by side, namely when the table is in contracted condition, will abut against certain of the legs 7, as illustrated of the pair of connected top sections 13 and 14 at the left-hand side of Fig. 1, and when shifted to the position for properly positioning them 85 for forming the extended table top will abut at their opposite ends against the legs 7 at the other ends of the base, in which condition the inner ends of the pairs of top sections occupy a position intermediate the 90 ends of the base 6, as illustrated of the connected sections 15 and 16 at the right in Fig. 1, and thus will be substantially in alinement.

In the normal contracted condition of the 100 table, the sections 14 and 15 extend in superposed condition on the sections 13 and 16, respectively, and these pairs of connected top sections extend side by side and centrally of the base 6, as illustrated of the full-line 105 representation of sections 13 and 14 in the upper half of Fig. 1 and the dotted line representations of the sections 15 and 16 in

the lower part of this figure, the table top thus produced being of a length corresponding with the length of any one of the four sections of the table top. To extend the 5 table the operator slides the pairs of connected table sections at their tongue and groove connections with the base in opposite directions to a point where the bars 17 carried thereby abut against posts 8 at opposite ends of the table, in which position the sections 15 and 16 assume the position represented by full lines in Fig. 1, and the sections 13 and 14 assume the position illustrated by dotted lines in said figure. Thus 10 operating the top sections produces diagonally disposed spaces at the corners of the table which are adapted to be filled by swinging the sections 14 and 15 in opposite directions at their hinged connections 19 with 15 the sections 13 and 16, respectively, thereby producing a rectangular table top of an area equal to the total area of the four sections forming the top of the table.

If desired, the sections 14 and 15 may be 20 locked to the sections 13 and 16 to render the structure stable and prevent accidental lifting of the sections 14 and 15. Any suitable means for this purpose may be employed, those shown comprising slide pins 25 or bolts 20 guidedly confined in casings 21 and adapted to be projected into sockets 22 in casing members 23, the casing 21 and 23 being arranged to align with each other when the table top is extended, as represented in Fig. 4.

While I prefer to provide the superposed hinged sections forming parts of the table top for filling up the diagonally disposed spaces at the corners thereof, when these sections 40 of the table top which are guidedly connected with the base are moved in opposite directions to extend the table, it will be understood that, if desired, the diagonally disposed spaces referred to may be filled by 45 top sections of suitable dimensions and disconnected from the sections 13 and 16. Furthermore, in carrying out the preferred embodiment of my invention wherein the sections of the table-top are self-contained 50 in the table, the arrangement of the underlying and superposed table-top sections may be variously modified and altered without departing from the spirit of my invention.

What I claim as new and desire to secure by Letters Patent is:

55

1. In a table, the combination of a non-extensible base provided with guide-means, and a top therefor formed of sections certain of which are superposed on, and hingedly connected with, the others thereof, said sections engaging said guide-means when said top is contracted and extended and movable on said base in opposite directions in parallel planes.

60

2. In a table, the combination of a base 65 and a top therefor formed of sections, certain of which are superposed on and hingedly connected at their inner edges with the others thereof, said sections being guidedly supported on said base to be movable thereon in opposite directions in parallel planes.

70

3. In a table, the combination of a base and a top therefor formed of a pair of underlying sections and a pair of superposed sections hingedly connected at their inner edges with said underlying sections at the inner edges of the latter, said pair of underlying sections being guidedly connected with said base to be movable thereon with said superposed sections in opposite directions and in parallel planes.

75

4. In a table, the combination of a base and a top therefor formed of sections arranged side by side certain of said sections 85 being superposed on, and hingedly connected at their inner edges with, the others thereof, said sections being guidedly confined on said base to be movable thereon longitudinally of each other in opposite directions in parallel planes.

90

5. In a table, the combination of a base and a top therefor formed of a pair of underlying sections and a pair of superposed sections hingedly connected at their inner 95 edges with said underlying sections at the inner edges of the latter, said pair of underlying sections being arranged normally side by side and guidedly connected with said base to be movable thereon with said superposed sections longitudinally of each other and in opposite directions in parallel planes.

100

PETER ALBANO.

In presence of—

HARRY J. ILETT,
JOHN W. HALL.
